UNITED STATES PATENT OFFICE.

LIBORIUS SENGE, OF CRESCENT SPRINGS, KENTUCKY.

SAFETY-POCKET.

1,111,678.

Specification of Letters Patent.

Patented Sept. 22, 1914.

Application filed May 29, 1914. Serial No. 841,858.

To all whom it may concern:

Be it known that I, LIBORIUS SENGE, a citizen of the United States, residing at Crescent Springs, in the county of Kenton and State of Kentucky, have invented certain new and useful Improvements in Safety-Pockets, of which the following is a specification, reference being had to the accompanying drawings.

10 This invention relates to new and useful improvements in safety pockets and more particularly to a device which is applied with a pocket-book, whereby the same is safely retained within the pocket, the primary object of the invention being the provision of a safety device which is used in combination with a garment pocket and includes a pocket-book having a strap attached thereto, which is adapted to be inserted through the bottom of the pocket and engaged with the portion of the garment upon the interior thereof to retain the pocket in such position that the pocket-book cannot be removed therefrom, without first detaching the strap.

Another object of the present invention is the provision of a device of the above character which will possess advantages in points of efficiency and durability, is inexpensive to manufacture and, at the same time, is simple in construction and operation.

With the above and other objects in view, the invention consists in the novel features of construction, combination and arrangement of parts as will be hereinafter referred to and more particularly pointed out in the specification and claim.

40 In the accompanying drawing forming a part of this application, Figure 1 is a detail perspective view of a safety pocket constructed in accordance with my invention, illustrating the device in an unfolded position. Fig. 2 is a similar view illustrating the device in its folded and fastened position; and Fig. 3 is a detail perspective view of the pocket-book.

In the accompanying drawing, I have illustrated my invention as applied to a 50 pair of trousers, which include the usual

hip pockets 1, one of said pockets being provided at its lower end with a central opening 2. My improved safety pocket device further includes a wallet 3, the outer body covering being provided with a slit 4 and arranged within this slit is the inner end of a strap or tab 5, said strap being held in position by means of a button 6. The tab 5 is adapted to be inserted through the opening 2 after the pocket-book or wallet has been placed within the pocket. After the pocket-book has been placed within the pocket member 1, the tab 5 is inserted through the opening 2 and the socket member 7, which is secured to the outer end of the tab is adapted to be engaged over the resilient head of the catch 8, which is secured to the upper portion of the trousers upon the inner side thereof. This operation folds the lower end of the pocket upon the upper end thereof and forms a safety device, whereby the pocket-book cannot be removed from the pocket, without first disengaging the socket 7 from the catch 8.

While I have shown and described the preferred form of pocket-book to be used in connection with my improved safety pocket, it will be apparent that this tab 5 may be applied to any form of pocket-book and used in the safety pocket equally as well. It will also be apparent that the device is extremely simple in its construction and can be manufactured and placed upon the market at a comparatively low cost.

85 While I have shown and described the preferred form of my invention, it will be obvious that various changes in the details of construction and in the proportions may be resorted to for successfully carrying my invention into practice, without sacrificing any of the novel features or departing from the scope of the invention, as defined by the appended claim.

Having thus described this invention, 95 what I claim is:—

In a safety pocket construction, the combination of a garment pocket provided with an entrance opening and another opening separate therefrom, with an article tab 100

adapted to be permanently attached to an article of value, said tab being insertible through the last mentioned opening, after the article has been passed through said entrance opening, and means for securing said tab to a garment with the pocket in an upwardly folded position.

In testimony whereof I hereunto affix my signature in the presence of two witnesses.

LIBORIUS SENGE.

Witnesses:

EUGENE H. JONAS,
CHRISTIAN KECK.
